United States Patent Office.

EDMUND BIGELOW, OF SPRINGFIELD, MASSACHUSETTS.

Design No. 3,509, dated June 1, 1869.

DESIGN FOR A SODA-FOUNTAIN.

The Schedule referred to in these Letters Patent and making part of the same.

To all whom it may concern:

Be it known that I, EDMUND BIGELOW, of Springfield, in the State of Massachusetts, have invented a new Design for the Outside Case of a Soda and Sirup-Fountain or Stand, termed "The Plain Cottage-Fountain," and I do hereby declare that the following is a full, clear, and exact description of the same, reference being had to the annexed drawing, making part of this specification, which drawing represents a perspective view.

My said design for the outside case of a soda and sirup-fountain consists in forming the said case in the style of a plain cottage-house.

In the annexed drawing, *a* and *b* represent the front and one end of a case for a soda and sirup-fountain. This case is made of marble. It is of oblong form, and of a sufficient height to answer the purpose required.

The two ends are formed alike, with a panel, *c*, each panel containing an ornamental frame, *d*, cut in relief, in the centre of which is a representation of the sun, setting behind a sheet of water.

The front and rear sides of the case do not extend up as high as the ends, and the ends are formed similar to the ends of a plain cottage, as represented in

the drawing, so that the cover or roof *f* may incline from the front and back, toward the centre of the case.

The top part *g* of the cover is made flat, that it may be used to set tumblers or other articles upon.

The inclined parts of the cover or roof are hinged to the flat part *g*, as shown at *h*, so that access can be had to the interior of the case.

The front and rear sides of the case are formed with a panel, *i*, as shown, and the front side is also provided, near the lower edge, with the usual faucets, *j*, for the drawing of the sirups, and near the top edge with the usual faucets, *k*, for the drawing of the soda and other waters.

At the top and bottom of the junction of the sides and ends of this case there are riveted metal clasps *l*, for the purpose of binding the case more securely together.

What I claim as new, and desire to secure by Letters Patent, is—

The design above described, and represented in the accompanying drawing, of a soda and sirup-fountain, formed in the style of a plain cottage-house.
